UNITED STATES PATENT OFFICE.

CHARLES S. BOCK, OF CHICAGO, ILLINOIS, ASSIGNOR OF FOUR ONE-HUNDREDTHS TO
WALTER J. O'BRIEN, THIRTY-TWO ONE-HUNDREDTHS TO JAMES W. SEWARD, AND
THIRTY-TWO ONE-HUNDREDTHS TO FRANK COLOMBO.

HINGE.

Application filed November 9, 1925. Serial No. 67,777.

This invention relates to a hinge mounting particularly for casement window sashes although it is capable of more general use and for instance, in connection with sashes and doors of domestic, office and store furniture.

A prime object is to develop a device of this character which will permit the sash, door or closure to be selectively swung from an axis at either of the opposed sides thereof.

Secondly, an aim is to provide a mounting of this character which will enable the change in movement of the closure from one axis to the other axis to be accomplished automatically by return of the closure to normal position and subsequent operation thereof in the appropriate direction.

A further important object is to produce a structure accomplishing the end stated which embodies a pair of hinge elements arranged so that one element resists movement of the other element should the closure tend to move laterally in parallelism to its frame, to thereby insure movement of the closure from a single axis at a time when otherwise moved with respect to its frame.

An operative embodiment of the invention as applied to a casement window is shown by way of example, in the accompanying drawings and from a consideration thereof additional objects and advantages will appear.

In said drawings:

Figure 1 is a view in elevation of the inner side of a casement window equipped with the present invention;

Figure 2 is a sectional view taken on the line 2—2 of Figure 1;

Figure 3 is a fragmentary elevation of the upper parts of Figure 1 and taken from the reverse side;

Figure 4 is a cross sectional view taken on the line 4—4 of Figure 3, but with the sashes in open position;

Figure 5 is a view similar to Figure 4, but with the sashes in another adjusted or open position;

Figure 6 is a sectional view taken on the line 6—6 of Figure 3 and

Figure 7 is a sectional view taken on the line 7—7 of Figure 3.

Referring specifically to the drawings, a conventional casement window frame 10 has

two similar sashes or closure members 11 fitted in a usual rabbet 12 at the outer or weather side of the frame. Said sashes 11 carry transparent panels 13. One of the sashes has a weather-strip 14 thereon overlapping the adjacent side of the companion sash.

Operatively positioned between the upper and lower ends of each sash or closure member 11 and the frame 10, is a hinge mounting A forming the prime feature of the present invention and which enable the sashes to be swung to the positions of either Figure 4 or Figure 5. The closures 11 may be locked in closed position by conventional catches as at B. Said catches B may each consist of a plate 15 secured to the sash and mounting a rotatable latch 16 which may engage the slot of a keeper 17 secured to the frame.

Each hinge mounting comprises a pair of hinge bars 18 and 19. Bar 18 at opposite ends and by means of pins 20 and 21 is pivoted to an attaching leaf or bracket 22 and to the horizontal wing 23 of an attaching leaf or bracket 24. Said leaves or brackets 22 and 24 are respectively screwed or otherwise fastened as at 25 to the adjacent sash or closure 11 and to the frame 10. The bars 19 are arranged inwardly of the bars 18 and each has a pin 26 and 27 at its opposite ends. Said pin 26 pivotally connects bar 19 with a leaf or bracket 28 screwed as at 29 to the adjacent closure 11. A horizontal portion 30 of a leaf or bracket 31 has the pin 27 pivotally connected thereto. Screws or the like 32 secure said bracket 28 to the closure 11.

Said bars 18 and 19 and associated parts of each mounting A are substantially completely located in the thickness of the associated closure or sash 11 accommodated in a recess or rabbet thereof as at 33 and substantially concealed from the outside by walls or extensions 34 on the closures 11. The pins 20 and 26, and 21 and 27, respectively, are in vertical alignment when the window is closed and the different parts of each mounting are in compact superposed relation with the bars 18 and 19 particularly in vertical alignment. Each of the brackets and bars 18 and 19 have offset por-

tions as at 35 where engaged by the pins 20, 21, 26 and 27 in order to outwardly offset said pins.

In the arrangement shown, should the 5 sashes tend to move transversely of the frame in parallelism thereto, such tendency will be counteracted or precluded since the bars 18 counteract the bars 19 by reason of the fixed pivots at opposite sides of the frames.

10 In this manner, the closures 11 must be swung in order to open them, and will swing on one axis at a time without interference by the parts which enable movement from the other axis.

15 Should it be desired to open the sashes or closures 11, as in Figure 4, the catches B are released and the sashes are pushed outwardly at their inner stiles and they swing from the pivot pins 20 and 26. During the 20 latter movement, the bars 19 move unitarily with the sashes. In order to open the sashes as in Figure 5, the outer vertical stiles of the sashes or closures are pushed outwardly, during which the sashes move on pivot 25 pins 21 and 27 with bars 18 moving unitarily with the sashes or closures. In moving from either of the positions contrasted in Figures 4 and 5, it is first necessary to move the sashes or closures to closed position and then 30 to the position desired because of the aforesaid arrangement of bars 19. The mountings B work automatically through movement of the sashes to adapt them for actuation to accommodate the sashes in the different 35 positions of the latter. Said sashes or closures 11 may further be so adjusted that either may be in the position of Figure 4 with the remaining one in the position of Figure 5.

40 The present application is a continuation in part of my application Serial No. 638,386, filed May 11, 1923 for an improvement in windows.

45 Various changes may be resorted to in the details of construction of my invention without departing from the spirit thereof or limiting its scope, and hence restriction to the precise details herein disclosed is not to be inferred.

50 What is claimed is:—

1. In combination with a closure member and a frame therefor, hinge members in normal position arranged substantially opposite each other, means pivoting one of the hinge 55 members adjacent an end thereof to the frame, means pivoting the other hinge member at the relatively opposite end thereof to the frame, and means in line with said means respectively pivoting the other ends of the hinge members to the closure members, said hinge members being located normally substantially within the thickness of the closure member.

2. In combination with a closure member and a frame therefor, hinge members in normal position arranged substantially opposite each other, means pivoting one of the hinge 65 members adjacent an end thereof to the

frame, means pivoting the other hinge member at the relatively opposite end thereof to the frame, and means in line with said means respectively pivoting the other ends of the hinge members to the closure members, said hinge members being located normally substantially within the thickness of the closure member.

3. In combination with a closure member and a frame therefor, hinge members in normal position arranged substantially opposite each other, means pivoting one of the hinge members adjacent an end thereof to the frame, means pivoting the other hinge member at the relatively opposite end thereof to the frame, means in line with said means respectively pivoting the other ends of the hinge members to the closure members, and said hinge members having offsets at each end in which the pivot elements are mounted.

4. In combination with a closure member and a frame therefor, hinge members in normal position arranged substantially opposite each other, means pivoting one of the hinge members adjacent an end thereof to the frame, means pivoting the other hinge member at the relatively opposite end thereof to the frame, means in line with said means respectively pivoting the other ends of the hinge members to the closure members, said hinge members being normally located substantially within the thickness of the closure member and extending substantially completely across the closure member, said hinge members having offsets at each end in which the pivot elements are mounted, and said closure member having a portion disposed in front of said members to substantially conceal the latter.

5. A hinge mounting comprising hinge elements normally arranged substantially in superposed aligned relation, means to pivotally secure said elements at relatively opposite ends to a relatively fixed member, means to pivotally secure said elements at the remaining ends to a relatively movable member, the latter means in the said relation of the elements being aligned with the adjacent first mentioned means.

6. A window construction comprising a frame, a sash, a pair of bars disposed one at the upper end and one at the lower end of the sash, said bars being pivotally connected to the frame at diagonally opposite corners and pivotally connected to the sash at diagonally opposite corners, a second pair of bars pivotally connected to the sash and frame in such manner as to permit swinging movement of the sash on either of the pivots of the first named pair of bars.

7. A window construction comprising a frame, a sash, a pair of bars disposed one at the upper end and one at the lower end of the sash, said bars being pivotally connected to the frame at diagonally opposite corners and

pivottally connected to the sash at diagonally opposite corners, a second pair of bars disposed one above and one below the ends of the sash and in parallel relation to the first named pair of bars, brackets pivotally connected to said second named pair of bars at diagonally opposite corners of the sash, said brackets being rigidly connected to the sash,

said second named pair of bars being pivotally connected to the frame at diagonally opposite corners whereby said sash may be swung outwardly into position transversely of the frame from either side edge of the sash.

CHARLES S. BOCK.
